[57] CLAIM

The ornamental design for a remote control unit bracket, as shown and described.

DESCRIPTION

FIG. 1 is a top perspective view of a remote control unit

bracket;

FIG. 2 is a bottom perspective view of the remote control unit bracket shown in FIG. 1;

FIG. 3 is a front elevational view of the remote control unit bracket shown in FIG. 1;

FIG. 4 is a left side elevational view of the remote control unit bracket shown in FIG. 1;

FIG. 5 is a top plan view of the remote control unit bracket shown in FIG. 1;

FIG. 6 is a right side elevational view of the remote control unit bracket shown in FIG. 1;

FIG. 7 is a bottom plan view of the remote control unit bracket shown in FIG. 1;

FIG. 8 is a rear elevational view of the remote control unit bracket shown in FIG. 1; and,

FIG. 9 is a top perspective view of the remote control unit bracket of FIG. 1, shown supporting a remote control unit (in phantom) in a docket position.

The broken line showing of a remote control unit is for illustrative purposes only and forms no part of the claimed design.
